Des. 212,807

Patented Nov. 26, 1968

212,807

CHRISTMAS TREE ORNAMENT

Dario Moranduzzo, Via Aretina 161,
Florence, Italy

Filed Apr. 3, 1968, Ser. No. 11,294

Term of patent 14 years

(Cl. D29—1)

FIG. 1

I claim:

The ornamental design for a Christmas tree ornament, as shown and described.
